CLAIM

The ornamental design for a front panel of a banknote handler, as shown and described.

DESCRIPTION

FIG. 1 is a top plan of a front panel of a bank note handler showing our new design;

FIG. 2 is a bottom plan view thereof;

FIG. 3 is a front view thereof;

FIG. 4 is an isometric view thereof;

FIG. 5 is a left side view thereof; and,

FIG. 6 is a right side view thereof.

The broken lines in the drawings are included for the purpose of illustration only and form no part of the claimed design.
